UNITED STATES PATENT OFFICE.

AARON S. NICHOLS, OF NEW YORK, N. Y.

HOLDER FOR DISK RECORDS.

1,066,138.

Specification of Letters Patent.

Patented July 1, 1913.

Application filed April 13, 1912, Serial No. 690,562. Renewed December 4, 1912. Serial No. 734,987.

To all whom it may concern:

Be it known that I, AARON S. NICHOLS, a citizen of the United States, residing in New York, in the county of New York and State of New York, have invented a new and useful Improvement in Holders for Disk Records, of which the following is a specification.

This invention relates to improvements 10 in holders for disk records such as are used in phonographs or talking machines.

The object of the invention is to provide a receptacle which is adapted to hold a number of such records which shall be inexpensive to manufacture, neat in appearance, compact and composed of few parts and so designed that there will be no danger of mutilating the surfaces of the records when the same are held in position.

Another object of the invention is to so 20 arrange the structure and parts that the force of gravity will be utilized to eject the disks or records from the case.

In the drawing forming a part of this 25 specification, Figure 1 is a front elevation of a structure embodying my improvements and Fig. 2 is a transverse, vertical section of the structure shown in Fig. 1.

In the drawings forming a part of this 30 specification, A represents the case, the same having a bottom 10, back 11 and top 12 and open at its front end. The case is provided with a plurality of vertical partitions 13 arranged diagonally, as shown in Fig. 2, 35 said partitions being spaced apart substantially the thickness of a disk and located between each pair of the partitions 13, or in other words, in each disk space is a pivoted lever or key 14, the same being pivoted 40 at its inner end on a rod 15 extending longitudinally of the case, each of said levers or keys 14 having its outer end normally pressed upwardly by a spring 16, the same being preferably seated in a socket 17 in the 45 bottom 10. The disks 18 are adapted to be supported on their rear edges by a block 19 extending longitudinally of the case, and provided with a sloping upper surface 20. Each of the keys or levers 14, if desired, 50 may be provided with an indicating disk 21 on its outer end, the same being provided with numerals corresponding to the numbers of the records. As shown in Fig. 2 of the drawing, each of the disks 18 will

be supported and retained in position by 55 means of the supporting member 19 and a lever 14, it being obvious that a portion of the lever 14 will engage the periphery of the disk at a point in front of and above the lowest point on the periphery of the disk. 60 In dotted line in Fig. 2 is shown the position assumed by a key or lever when the same is depressed, and as will be obvious, the disk 18 will roll down the inclined surface 20, due to the force of gravity, and down 65 and over the lever 14 to a position in the front of the case, where the same may be grasped by the fingers and removed from the case. As soon as the lever or key 14 is released after the disk has been removed, 70 the same will return to normal position, and is preferably limited in its upward movement by a projection 22 extending along the front edge of the supporting block or member 19. 75

I have shown and described one form of construction embodying my improvements, but as will be obvious, various changes and modifications may be made in the details of construction of the same without departing from the spirit of the invention, and all such changes and variations are contemplated as fall within the scope of the claim appended hereto.

I claim:

A holder for record disks comprising in combination, a suitable case having vertical partitions dividing it into individual disk spaces, means for supporting and retaining the disks in place and above the bottom of the case comprising a plurality of pivoted levers, one in each disk space, each of said levers being pivoted at its inner end and having a portion adapted to engage a disk at a point on the periphery in front of and above the lowest point thereof to retain the disk in place in the case against the force of gravity, and springs for each of said levers normally urging the outer ends upwardly, each of said levers being adapted to have its outer end depressed against the action of the spring, and thereby to allow the disk to roll out by gravity, substantially as specified.

AARON S. NICHOLS.
